Filed Mar. 13, 1972, Ser. No. 234,462

Term of patent 14 years

Int. Cl. D6—06

U.S. Cl. D6—130

FIG. 1 is a perspective view of a removable message center for a wall mounted telephone, showing my new design, with the words Telephone, Address and Notes shown in broken lines for illustrative purposes only;

FIG. 2 is a left side elevational view of the device of FIG. 1; and

FIG. 3 is a bottom plan view of the device of FIG. 1. The chain broken away at the center portion thereof in FIGS. 1 and 2 indicates indeterminate length.

I claim:

The ornamental design for a removable message center unit for a wall mounted telephone, as shown and described.
